(57) **CLAIM**

The ornamental design for a dual handle rowing machine as shown and described.

DESCRIPTION

FIG. 1 is a front and top perspective view of a dual handle rowing machine according to the present invention;

FIG. 2 is a front view of a dual handle rowing machine according to the present invention;

FIG. 3 is a rear view of a dual handle rowing machine according to the present invention;

FIG. 4 is a left-side view of a dual handle rowing machine according to the present invention;

FIG. 5 is a right-side view of a dual handle rowing machine according to the present invention;

FIG. 6 is a top view of a dual handle rowing machine according to the present invention;

FIG. 7 is a bottom view of a dual handle rowing machine according to the present invention;

FIG. 8 is an enlarged view of FIG. 1; and,

FIG. 9 is an enlarged view of FIG. 1.

The dash-dash-dot broken lines in FIG. 8 and FIG. 9 represent the bounds of the enlargement taken from FIG. 1 and form no part of the claimed design.

The dash-dash broken lines are for illustrative purpose only and form no part of the claimed design.
